UNITED STATES PATENT OFFICE.

ELEANOR C. O'CONNELL, OF CINCINNATI, OHIO.

DESIGN FOR A BREASTPIN.

SPECIFICATION forming part of Design No. 15,638, dated December 23, 1884.

Application filed September 18, 1884. Term of patent 14 years.

To all whom it may concern:

Be it known that I, ELEANOR C. O'CONNELL, a citizen of the United States, residing at Cincinnati, in the county of Hamilton and State of 5 Ohio, have invented and produced a new and original Design for Breastpins, of which the following is a specification, reference being had to the accompanying drawings, forming part thereof.

Figure 1 is a front view of my newly-designed breastpin, enlarged. Figs. 2 and 3 are rear views of same.

The leading feature of my design consists in the shield A, with steps B on each side, beginning at the base of the shield and gradually approaching the top, so that it will be pyramidal in shape, as shown in the respective figures of the drawings.

J represents the jewels placed at each angle of the shield. 20

I claim—

1. The design for a breastpin, consisting of a shield the sides of which represent the outline of a pyramid in elevation, as described and shown. 25
2. In a design for a breastpin, a shield representing a stepped pyramid, and with jewels J at each angle, substantially as shown.

ELEANOR C. O'CONNELL.
